UNITED STATES PATENT OFFICE

MAX KLINE, OF NEW YORK, N. Y.

ATOMIZER

Application filed April 20, 1928. Serial No. 271,598.

This invention relates to dispensing containers, and has particular reference to an improvement in containers for atomizing and spraying the contents thereof.

5 The invention primarily comprehends an improved atomizing or spray head which effects the simplification of the construction and assembly of the parts, and an economy in its production without detracting from its efficiency.

10 The invention further aims to provide an improved means for attaching the spray or atomizer head to the container which in addition to facilitating the filling of the container effects an economy in the production and a simplification of the construction thereof.

15 With the above recited and other objects in view, reference is had to the following description and accompanying drawings, in which there is exhibited one example or embodiment of the invention, while the claims define the actual scope of the same.

20 In the drawings:

25 Figure 1 is a side view of the atomizer constructed in accordance with the invention, parts being broken away and shown in section to disclose the underlying structure.

30 Figure 2 is a collective perspective view of the atomizer head parts separated and in juxtaposition.

35 Figure 3 is a collective view of the elements of the means for attaching the atomizer head to a container.

40 Referring to the drawings by characters of reference, 10 designates an atomizer or spray head having a longitudinally extending vertically disposed liquid passage 11 and a transverse opening 12 intersecting said liquid passage. An air tube 13, to the rear end of which the usual bulb 14 is attached, has its usual bore 15 enlarged adjacent its forward terminal portion as illustrated at 16, the juncture of the enlarged bore portion 16 with the remainder of the bore defining the shoulder 17. The enlarged bore portion 16 is formed with a liquid port 18 which when the air tube is inserted in the opening 12 is designed to communicate with the liquid passage 11. A nozzle 19 is forced into and snug-

ly fits within the enlarged bore portion with its innermost end impinged against the shoulder 17. The nozzle is provided with a substantially concentric air passage 20 communicating with the bore 15 of the air tube and said nozzle is further provided with a longitudinally extending exterior groove 21 which is designed to register with the liquid port 18. The nozzle is designed to be inserted in the enlarged bore 16 of the air tube after the air tube has been initially inserted in the opening 12 so that the nozzle functions to radially expand that portion of the tube having the enlarged bore, thus effectually retaining the air tube in the head against possible rotatory or axial movement. The extremity 22 of the air tube which protrudes from the head is preferably rolled or spun inwardly to define a restricted passage port 23.

55 In order to provide means for attaching the head to the neck end of the liquid container C, a stopper 25, preferably of cork, is carried by the head and is adapted to frictionally fit within the neck of the container. A covering apron 26 is also carried by the head and is adapted to fit over the outside of the neck end to lend a finished appearance to the atomizer in addition to concealing the cork where the container is of glass or other transparent material. Preferably, the cork is attached to the head by an exteriorly threaded sleeve 27, the upper end of which is threaded into a threaded recess 28 in the head 10 while the stopper is formed with a threaded bore 29 engaging the remaining depending portion of the sleeve. An aspirator tube 30 has its upper end threaded at 31 to engage within a threaded recess 32 in the lower end of the sleeve, the aspirator tube 30 extending downwardly to a point adjacent the bottom of the container.

60 In use, squeezing of the bulb 14 causes air to flow through the bore 15 of the air tube, thence through the air passage 20 of the nozzle where a suction is created within the outer end of the nozzle to draw the liquid from the container through the aspirator tube, the bore of the sleeve, the liquid passage 11, the liquid port 18 and the groove 21 in the

65 70 75 80 85 90 95 100 105 110

nozzle where it is mixed with the air and discharged as a spray through the discharge opening 23. When it is desired to refill the container C, it is obvious that the head, including the stopper, apron, sleeve and aspirator tube, are disconnected or removed from the container which affords a large opening mouth through the neck for the filling operation.

10 1. What is claimed is:

1. An atomizer head having a transverse opening, an air tube in the transverse opening having a portion of its bore enlarged to form a shoulder, the enlargement of the bore 15 extending to a terminal of the air tube, the said tube having a liquid port communicating with the enlarged portion of the bore and with a liquid passage extending inwardly from one end of the head, and a nozzle disposed in the enlarged portion of the bore with one end against the shoulder, the nozzle serving to press the sides of the air tube outwardly and against the atomizer head at the transverse opening to hold the air tube in position 25 relatively to the atomizer head, the nozzle having a central air passage communicating with the air tube bore and a longitudinally extending groove registering with the liquid port.

2. An atomizer head having a transverse opening, an air tube in the transverse opening having a portion of its bore enlarged to form a shoulder, the enlargement of the bore extending to a terminal of the air tube, the 35 said tube having a liquid port communicating with the enlarged portion of the bore and with a liquid passage extending inwardly from one end of the head, and a nozzle disposed in the enlarged portion of the bore 40 with one end against the shoulder, the nozzle serving to press the sides of the air tube outwardly and against the atomizer head at the transverse opening to hold the air tube in position relatively to the atomizer head, the 45 nozzle having a central air passage communicating with the air tube bore and a longitudinally extending groove registering with the liquid port, the sides of the terminal of the air tube beyond the other end of the nozzle converging to define a restricted passage.

3. An atomizer head including an air tube extending therethrough having the terminal portion of its bore enlarged to provide an internal shoulder, said tube having a liquid 55 port communicating with the enlarged portion of the bore and with a liquid passage extending inwardly from one end of the head and a nozzle snugly fitting in the enlarged portion of the bore with its inner end impinged against the shoulder, said nozzle having a substantially concentric air passage communicating with the air tube bore and a longitudinally extending groove registering with the liquid port.

65 4. In an atomizer, a head having a liquid

passage, a transverse opening intersecting said passage, an air tube extending therethrough having relatively small and large bores defining an internal shoulder, said air tube having a liquid port communicating with the larger bore and registering with the liquid passage and a nozzle snugly fitting within the enlarged bore with its inner end engaging the shoulder, said nozzle having an air passage extending axially thereof and communicating with the reduced bore of the air tube, said nozzle having a longitudinally extending exterior groove communicating with the liquid port and defining together with the air tube wall a liquid passage.

5. In an atomizer, a head having a liquid passage, a transverse opening intersecting said passage, an air tube extending therethrough having relatively small and large bores defining an internal shoulder, said air tube having a liquid port communicating with the larger bore and registering with the liquid passage and a nozzle snugly fitting within the enlarged bore with its inner end engaging the shoulder, said nozzle having an air passage extending axially thereof and communicating with the reduced bore of the air tube, said nozzle having a longitudinally extending exterior groove communicating with the liquid port and defining together with the air tube wall a liquid passage, the outer forward end of the air tube having an inwardly rolled terminal to provide a restricted discharge opening for the atomized liquid.

Signed at New York in the county of New York and State of New York this 9 day of April A. D. 1928.

MAX KLINE.
